Primary Examiner — Clare E Heflin(74) *Attorney, Agent, or Firm* — Kilpatrick Townsend & Stockton LLP(57) **CLAIM**

The ornamental design for a wine barrel lighting stand, as shown and described.

DESCRIPTION

FIG. 1 is a perspective view of the wine barrel lighting stand showing the new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof;

FIG. 7 is a right side elevational view thereof; and,

FIG. 8 is another perspective view thereof showing only the claimed portion of the design.

The broken lines in the drawings are for illustrative purposes only and form no part of the claimed design.
